UNITED STATES PATENT OFFICE.

SAMUEL ROSEN, OF UTICA, NEW YORK.

DESIGN FOR A CURTAIN-HOLDER.

52,345.

Specification for Design.

Patented Aug. 27, 1918.

Application filed April 26, 1918. Serial No. 231,044. Term of patent 14 years.

To all whom it may concern:

Be it known that I, SAMUEL ROSEN, a subject of the late Russian Empire, having declared my intention to become a citizen of the United States, residing at Utica, in the county of Oneida and State of New York, have invented a new, original, and ornamental Design for Curtain-Holders, of which the following is a specification, reference being had to the accompanying drawing, forming part thereof.

Fig. 2 is a perspective view of a curtain holder, showing the reverse side from that illustrated in Fig. 1.

I claim:

The ornamental design for a curtain holder, as shown.

SAMUEL ROSEN.
